UNITED STATES PATENT OFFICE.

JAMES WAYLAND, OF NEWARK, NEW JERSEY, ASSIGNOR OF ONE-HALF TO
THOMAS H. BROWN, OF SAME PLACE.

SHUTTER-WORKER.

SPECIFICATION forming part of Letters Patent No. 365,357, dated June 21, 1887.

Application filed October 25, 1886. Serial No. 217,294. (No model.)

To all whom it may concern:

Be it known that I, JAMES WAYLAND, a citizen of the United States, residing at Newark, in the county of Essex and State of New Jersey, have invented certain new and useful Improvements in Shutter-Workers; and I do hereby declare the following to be a full, clear, and exact description of the invention, such as will enable others skilled in the art to which it applies to make and use the same, reference being had to the accompanying drawings, and to letters of reference marked thereon, which form a part of this specification.

The object of this invention is to more effectively protect the exposed mechanism of the worker from the clogging effect of ice or snow; to secure a more certain and efficient co operation of parts; to provide increased strength, whereby the worker can more certainly withstand the effect of wind on the shutter; to reduce the cost of construction and simplify the device.

The invention consists in the improved shutter-worker having the arrangements and combinations of parts, substantially as will be hereinafter set forth, and finally embodied in the clauses of the claim.

Referring to the accompanying drawings, in which like letters indicate corresponding parts in each of the several figures of the two sheets thereof, Figure 1 is a side elevation of a portion of a window-frame having the improvements attached thereto. Figs. 2 and 7 are detail views of operating-bars adapted to pass through said frame from the outer hinge to the interior of the house, the former of said figures illustrating a preferred construction. Figs. 3 and 4 are plans of the shutter-sections of said hinge, the former showing the preferred construction. Fig. 5 is a side elevation of the house-section of said hinge. Fig. 6 is a sectional view of the operating-bar, taken through line x , Fig. 7. Fig. 8 is a front elevation of the interior plate adapted to be secured upon the inner casing of said frame and provide bearings for the operating-bar above mentioned, and hold the same in a fixed position to resist any action of the shutter. Fig. 9 is a sectional view of an outer plate providing bearings for the outer end of said bar. Fig. 10 is a front elevation of a portion of a shutter and shutter-

frame provided with my improved window-worker; and Figs. 11, 12, and 13 are enlarged details showing certain parts of the same.

In said drawings, a indicates a portion of the sash; b , a portion of the shutter, of any suitable construction; c , a hinge-section for the house, and d a hinge-section secured to the shutter, the last being provided with a caged portion, d' , the preferred construction of which is shown in plan in Fig. 3.

e indicates the operating-bar adapted to engage said caged portion of the shutter-section, and by a straight backward and forward movement to cause said shutter-section to revolve with the shutter upon the co-operating section a . The said operating-bar e extends through suitable openings or perforations, ff , in the window-frame, and at the inner end is provided with a suitable handle, g , by which the said operating-bar is manipulated. The outer end of said bar projects through and from said frame, and is preferably provided with a series of perforations, $h h$, to receive the cogs d' of the hinge. Said perforations extend horizontally through said bar, as shown in Figs. 1, 2, and 9, said bar being provided at the upper and lower edges with connecting flanges or portions h' , which give strength to said bar and protect the openings to a certain extent from the entrance of rain and snow, which, freezing fast, would tend to clog said openings. The said openings extend entirely through the bar. Should they become clogged with frozen moisture, upon the introduction of the cogs at one side the said frozen matter may be readily forced out at the opposite side by said cogs, so that the operation of the device is not interfered with. To prevent said frozen matter from clogging the hinge-sections d , co-operating with said bar, the same is, at the base of the cogs, provided with blade-like formations d'' , formed by contracting the metal at the base of said cogs to an edge, as shown in Fig. 3. When the caged or toothed portions of the bar enter the spaces between the cogs, should said spaces be filled with said frozen matter, the same is forced against the said edges or blade-like formations, and thus is forced out of said spaces, so that the operation of the device at this point also will not be hampered.

While I prefer the constructions of the hinge-

sections *d* and bar *e* thus specified, other constructions may be employed in connection with other features of this invention.

To hold the operating-bar more firmly and securely into operative engagement with the cogged shutter-section, so that the said bar cannot be forced away from said cogged portion when the parts are in motion, I have provided or may provide integral with the hinge-plate 5 a projecting brace, *i*, having an anti-friction roller thereon to reduce the friction occasioned in operating the worker, which roller bears on the said bar at a point thereon opposite the point of engagement of said bar with the cogs 15 of the hinge-section.

The house-section of the hinge *c* is provided with a suitable perforation, through which the bar *e* extends and finds its bearings.

The inner end of the bar may be provided 20 with a series of notches, *j*, in its lower edge, to engage a stop-plate, *k*, Fig. 1, and limit the longitudinal movement of the operating-bar. This bar may engage said stop-plate automatically under the influence of gravity, or I may, 25 and I prefer to, employ a spring, *l*, as by the use of the latter I secure a more certain engagement.

In lieu of the notches and co-operating stop *k*, I prefer to employ an automatic clamping 30 device, (illustrated in Fig. 8,) in which case I provide one side of the bar with longitudinal grooves *m*, Fig. 7, and on the inner casing of the frame or the bearing-plate *n* thereon I arrange an eccentric pawl, *o*, which is toothed in 35 correspondence with the grooves of the bar and engages the same, substantially as shown in Fig. 8. By means of the co-operating grooves and teeth the eccentric and operating-bar are held in the same general relation, so 40 that the said bar can only be held or clamped when in its lowest position in the bearing-plate when forced down automatically by the spring.

The bar works in a vertical slot in said plate *n*, and by raising the said bar the pawl, while 45 still engaging the teeth, is relieved of clamp-

ing pressure, so that said bar may be readily moved longitudinally in the slot. By releasing the hand from the said bar the spring *l* acts automatically to depress the bar and the latter causes the pawl to descend with it, so that 50 the said parts are brought again into clamping relation, the bar being pressed hard against the side of the slot.

The operation of the device is apparent, and needs but little explanation. By raising the 55 handle and drawing it out toward the person in the room, the shutter is opened. The reverse action tends to close said shutter. By raising the handle the bar may be easily moved backward or forward. By releasing 60 the handle the bar drops automatically, and the pawl immediately acts to prevent longitudinal movement of the bar, so that the shutter may be held at any desired point within the limits of its movement.

65

Having thus fully described my invention, what I claim as new is—

1. In a shutter-worker, the combination, with an operating-bar, of a cogged section, *d*', provided with blade-like conformations at the 70 base of the cogs thereof, substantially as and for the purposes set forth.

2. In a shutter-worker, the combination of the operating-bar having longitudinal grooves, and an eccentric, *o*, toothed in correspondence with said grooves.

75

3. In a shutter-worker, the combination, with the operating-bar, of hinge-sections, one of which is cogged to engage said operating-bar, and the other provided with a projecting 80 brace, *i*, carrying an anti-friction roller, said parts being arranged and combined substantially as and for the purposes set forth.

In testimony that I claim the foregoing I have hereunto set my hand this 13th day of 85 October, 1886.

JAMES WAYLAND.
